UNITED STATES PATENT OFFICE.

EDWARD J. O'CLAIR, OF NASHUA, NEW HAMPSHIRE, ASSIGNOR TO NASHUA GUMMED & COATED PAPER COMPANY, OF NASHUA, NEW HAMPSHIRE, A CORPORATION OF MASSACHUSETTS.

PROTECTING AND DISPENSING PACKAGE.

Application filed November 20, 1926. Serial No. 149,597.

This invention relates to the packaging of a plurality of articles in a manner that will enable them to be removed singly without disturbing the others, and has particular reference to so packaging such articles as coils of gummed tape that they will be protected from the access of moisture thereto even after one or more of the articles have been removed from the package.

- 10 The use of gummed paper or gummed tape is very extensive. It is usually produced and stored and sold in the form of coils from which it is drawn for use such as the fastenings for bundles, in place of string.
- 15 If a coil of dry-gummed tape is exposed to dampness, it deteriorates and becomes adhesive and the freedom of un-coiling for use is impaired. It is not convenient to wrap each coil separately, and a common practice of
- 20 packaging such disk-shaped articles for storage, transportation, and sale, has been to assemble a number of the coils in flat contact with each other and enclose them in a suitable wrapper, the complete package being
- 25 in the form of a roll. Then when a coil is wanted for use, the wrapper must be torn or broken at one end or more or less along one side of the roll. In the latter case some or all of the coils which are not immediately
- 30 wanted are no longer protected by the wrapper; while if the wrapper is carefully opened only at one end it is difficult to remove the coils singly after the first one or two have been picked out. Moreover, even when only
- 35 one end of the wrapper has been opened, the top or end coil remaining after each removal is liable to be affected by moisture.

The object of my invention is to produce packages of articles such as referred to, each of which packages will enable the articles to be easily removed singly and successively through one open end of the roll, even to the last article, without reducing the protecting capacity of the wrapper or container.

45 A further object is to produce packages which will permit the removal of the articles singly and yet leave the next and all remaining articles fully protected from dampness or dust.

50 With these objects in view, the invention consists in the packages substantially as hereinafter described and claimed.

Of the accompanying drawings which illustrate my invention in one of its embodiments,

55 Figure 1 illustrates a package in its fully closed and sealed condition, partly broken out to reduce length of the figure.

Figure 2 is a similar view, but indicating a portion of the wrapper or container broken away to illustrate the relationship of the packages and the dispensing strip.

60 Figure 3 is a similar view illustrating how the dispensing strip serves to raise each package, one at a time.

65 Figure 4 is a plan view of the end of a package which has been opened, a portion of the dispensing strip being broken away.

70 Similar reference characters indicate similar parts or features in all of the views.

The articles *a*, in the present instance coils of gummed tape, are assembled with a strip *b* arranged as presently described and enclosed in a container *c*, usually of strong and waterproof paper which is so wrapped as to hold the assembly in the form of a roll and with the end portions of the wrapper sealed down.

75 The strip *b* is, preferably, of a width equal to or slightly exceeding the diameter of the rolls, for a reason presently explained. Said strip is so assembled with the articles *a* that it extends in alternate opposite directions between the articles. Preferably one end (the bottom end when the roll or package is upright as illustrated) extends under the lowermost article, then up past one edge and over the top of that article, then up past the edge of the second article and back over its top, and so on until the last article of the collection can be covered by the other end of the strip, as illustrated by Figure 2. The wrapper or container *c* encloses the whole.

80 When an article is wanted, one end of the container is opened (Fig. 4) and the end of the strip *b* is pulled or lifted so as to tilt or lift the first article far enough to enable it to be grasped and removed, after which said strip can be folded back on itself so as to cover and protect the next article. This operation is simply repeated as successive

85 articles are wanted, successive operations finally emptying the container. Of course if the container is very long, having a large

number of articles therein, portions of its length which have been emptied can be torn or cut away.

The reason for employing a strip having the width above referred to is to protect each article next to the one removed. When the articles in the package are of a character which should be protected from moisture, such as gummed paper, the strip *b* is preferably of waterproof or moisture-proof paper.

While my invention is particularly applicable to the packaging of coils of gummed tape, I do not limit myself thereto as a wide variety of other articles can be advantageously similarly packaged for protection and dispensing purposes.

Having now described my invention, I claim:

20 1. The combination with a container having a plurality of rolls of gummed tape packed therein, of a flexible moisture-proof strip extending alternately in opposite di-

rections between the rolls, whereby said rolls may be successively lifted singly to facilitate 25 their removal from the container.

2. A protecting and dispensing package for a plurality of rolls of gummed tape, consisting of an enclosure surrounding the rolls and a flexible moisture-proof strip extending alternately in opposite directions between the rolls, said strip having a width to 30 completely cover each roll that is next to one which has been removed.

3. A protecting and dispensing package 35 for a plurality of rolls of gummed tape, consisting of an enclosure containing said rolls, said enclosure having an end portion which may be opened and constructed to retain its form when the end is opened, and a flexible 40 moisture-proof strip extending alternately in opposite directions between said rolls.

In testimony whereof I have affixed my signature.

EDWARD J. O'CLAIR.
